UNITED STATES PATENT OFFICE.

EDWARD A. LEWIS, OF ST. LOUIS, MISSOURI.

TIME-PIECE DIAL.

SPECIFICATION forming part of Letters Patent No. 374,605, dated December 13, 1887.

Application filed December 12, 1883. Serial No. 114,346. (No model.)

To all whom it may concern:

Be it known that I, EDWARD A. LEWIS, of St. Louis, Missouri, have made a new and useful Improvement in Time-Pieces, of which the following is a full, clear, and exact description, reference being had to the annexed drawings, making part of this specification, in which—

Figure 1 is a front or face elevation of a time-piece having the improvement; Fig. 2, a similar elevation, the rear dial-plate being moved; Fig. 3, a front or face elevation of the rear dial-plate; Fig. 4, an edge elevation of the parts shown in Figs. 1 and 2; Fig. 5, a section on the line 5 6 of Fig. 4, the view being looking toward the rear dial-plate; Fig. 6, a similar section, the gearing and levers being in a different position and the dial-plate being shifted; Fig. 7, a section upon an enlarged scale on the line 7 7 of Fig. 5, and Fig. 8 a section upon an enlarged scale on the line 8 8 of Fig. 5.

The same letters of reference denote the same parts.

This invention consists, mainly, in providing a time-piece with a graduation so made and so related to the remaining parts of the time-piece that it can be used partly as a twelve-hour and partly as a twenty-four-hour graduation. By means of it the ordinary hands can be used and in the ordinary way. Up to midday the ordinary twelve-hour graduation appears, and from midday to midnight the twenty-four-hour graduation is used, the numbers of which appear in the places respectively occupied by those of the ordinary twelve-hour graduation.

A represents what may be termed the "front" dial-plate, for it occupies the place of the ordinary dial-plate of a clock or watch, and it is provided with the ordinary minute graduation, a.

B represents the ordinary hour-hand, and C the ordinary minute-hand. These hands are made and operated in the ordinary manner. The plate A has a series of openings, a' a' a', at the points, respectively, of the plate hitherto occupied by the numbers of the ordinary twelve-hour graduation. Behind the plate A is what may be termed the "rear" dial-plate, D. Upon this last-named plate is a gradu-

tion, d. This graduation, as shown in Fig. 3, has twenty-four numbers, arranged as follows: At the top, where the number 12 appears in the ordinary twelve-hour graduation, the number 24 appears, then the number 1, then the number 13, then the number 2, then the number 14, then the number 3, and so on. The space between the numbers 24 and 13, as well as that between the numbers 13 and 14 and between the numbers 14 and 15, and so on, as well as the space between the numbers 1 and 2, between the numbers 2 and 3, and between the numbers 3 and 4, and so on, is equal to the space between any of the adjoining numbers of the ordinary twelve-hour graduation. This dial-plate D is adapted to be rotated reciprocatingly, so that the numbers 12, 1, 2, 3, 4, &c., can appear in the openings a' of the plate A, as in Fig. 1, or so that the numbers 24, 13, 14, 15, &c., can appear in the openings a', as in Fig. 2.

The operation of the invention as thus far described is as follows: At midnight the number 24 appears at the top opening, a', of the plate A. After midnight and at any time during the ensuing hour the plate D is rotated upon its center d', so as to present the numbers 12, 1, 2, 3, &c., as in Fig. 1. The dial D then remains in the last-named position until midday, after which and during the hour ensuing midday the plate D is rotated backward into its original position, in which position the numbers 24, 13, 14, 15, &c., will appear, as in Fig. 2. Thus during the first half of the twenty-four hours the dial of the time-piece presents substantially the appearance of the ordinary time-piece; but during the second half of the twenty-four hours it presents the view shown in Fig. 2; and as the new numbers 13, 14, 15, &c., appear in the same relative places hitherto occupied by the ordinary numbers 1, 2, 3, &c., it becomes much easier for one to become familiarized with the new graduation incident to the adoption to what is known as the "twenty-four-hour standard."

Various forms of mechanism may be employed for reciprocating the dial-plate D in the manner described. That which I consider a desirable form is shown in Figs. 4, 5, 6, 7, 8.

E represents a pinion attached to the hour-hand spindle F, and rotating once in twelve

hours. It engages with and drives the gear G. This last-named gear has twice as many teeth as the pinion E. It turns upon the spindle g, and has attached to it the cam I. 5 J and K represent levers turning loosely upon the bearing F. At one end they are each provided with a stud, j k, for the purpose of engaging with the cam I. The other ends of the levers are adapted to be drawn toward 10 each other by means of the springs j' k', respectively—that is, the springs at one end are fastened to some fixed part of the frame of the time-piece, such as the post L, and the other ends of the springs are attached, respectively, to the levers J K. The movement 15 of the cam, as indicated by the arrows, causes the levers to be oscillated in one direction upon the bearing F, and the springs operate, when the levers are released by the cam, to 20 move the levers back again into their original positions—that is, more particularly described, when after midnight it is desired to shift the dial-plate D, the gearing and cam are adjusted so as to allow the lever K to move 25 from the position shown in the dotted lines in Fig. 6 into the position shown in the full lines in that figure. In this movement the lever K encounters the stud d² upon the dial-plate D, and in consequence causes the dial-plate D to 30 be moved as desired. Meanwhile the other lever J is in the position shown in the full lines in Fig. 6. After midday, when it is desired to shift the dial-plate D back again, the cam I will have been turned around into the

position shown in Fig. 5, whereupon the lever J moves from the position shown in the dotted lines in Fig. 5 into the position shown in the full lines in Fig. 5, and in this movement it encounters the stud d³, causing the dial-plate D to be moved in the manner last described. 40 The levers J K oscillate upon the spindle F independently of each other, and, as shown in Fig. 7, it is desirable for them to be separated from each other by suitable washers, M.

The dial D, while intended to be oscillated, as 45 described, upon the bearing F, should, after having been shifted, as described, be kept from being accidentally displaced. For this purpose some suitable means—such as a washer, N, Fig. 7—may be attached to the bearing F, and 50 so as to bear slightly against the dial-plate D. Then, after the dial-plate D has been shifted into either of its positions, the rotation of the cam I causes the lever last used in shifting the dial-plate to be moved backward from the 55 stud d² or d³, as the case may be, and the lever remains away from the stud until the dial-plate has by means of the other lever been shifted back again.

I claim—

The combination of the dial-plate D, having the studs d² d³, the spindle F, the pinion E, the gear G, the cam I, the levers J K, and the springs j' k', substantially as described.

EDWD. A. LEWIS.
